(57) **CLAIM**

The ornamental design of a top- and rear-mounted storage containers and framed shield, as shown and described.

DESCRIPTION

FIG. 1 is a front, top, left side perspective view of the top- and rear-mounted storage containers and framed shield, showing our new design;

FIG. 2 is a front side elevational view thereof;

FIG. 3 is a rear side elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The features shown in broken lines depict environmental structure only and form no part of the claimed design.
